(57) **CLAIM**

The ornamental design for a condom package, as shown and described.

DESCRIPTION

FIG. 1 is a perspective view of a condom package, showing the inside and outside of the package;

FIG. 2 is a perspective view of the outside of the package shown partially folded;

FIG. 3 is perspective view of the inside of the package shown partially unfolded;

FIG. 4 is perspective view of the inside of the package shown partially unfolded; and,

FIG. 5 is a perspective view of another side of the outside of the package in a folded condition.

The broken line showing is for illustrative purposes only, and forms no part of the claimed design.
